UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

WARNING-SIGNAL DEVICE.

1,135,600.

Specification of Letters Patent. Patented Apr. 13, 1915.

Application filed July 30, 1914. Serial No. 854,045.

To all whom it may concern:

Be it known that I, RAY H. MANSON, a citizen of the United States, residing at Elyria, Lorain county, Ohio, have invented 5 certain new and useful Improvements in Warning-Signal Devices; and I do hereby declare the following to be a full, clear, and exact description of the invention, such as will enable others skilled in the art to which 10 it appertains to make and use the same.

My invention relates to warning signal devices, such as are adapted to be used upon motor driven vehicles, for fog horns, or wherever it is desired to give a warning 15 signal.

My invention more particularly relates to a type of signal of this character in which a diaphragm is actuated by a roughened wheel.

20 The particular objects of my invention and the invention itself will probably be better understood from a detailed description of an embodiment of the invention.

Figure 1 is a plan view of an embodiment 25 of my invention with the rear casing removed, a portion of the apparatus being shown in section. Fig. 2 is a cross-sectional view of the embodiment shown in Fig. 1. Fig. 3 is an end view of the motor employed 30 in the embodiment illustrated in Figs. 1 and 2. Fig. 4 is a view of the motor showing one of the field coils in section. Fig. 5 shows the end of the motor opposite from that shown in Fig. 3. Figs. 6, 7 and 8 are 35 details showing the roughened wheel employed for operating the diaphragm.

Referring now to the embodiment illustrated in the drawing, at 10 I show a frame piece or supporting member, which is here 40 shown as provided with a large opening 11 in the central portion thereof. As will be seen, the frame piece 10 is flat, so that it occupies but little space. A casing front 12 is provided, struck up, as shown at 13, to 45 form a chamber for the diaphragm. As a draft must flow through this chamber to permit its clearance of foreign matter entering through the resonator, it is made large so that there will always be clearance for 50 the draft, even when the diaphragm is in its maximum forward position. An opening 14 is formed in the casing front, preferably in the central portion thereof. A resonator 15 may be provided connected in 55 any suitable manner to the casing front.

In the form shown the casing front about the opening 14 is turned up, as shown at 16 and the resonator is connected thereto in any suitable manner.

The sonorous member, here shown as a 60 vibratile diaphragm, is illustrated at 17. The diaphragm is clamped between the front and frame piece, as illustrated, and connected thereto by suitable means, such as screws 18. In the form shown, the dia- 65 phragm, the frame piece and casing front are perforated, and the screws driven through these perforations tightly drawing and holding the parts together, I prefer to insulate these parts and separate them by 70 some suitable means, such as cork washers 20.

The outer edges of the front casing piece are turned back, as shown at 21, leaving a small space 22 between the annular member 75 21 and the frame piece, in order that the edges of the casing back 24 may be slipped in between these members. The diaphragm actuating means is mounted upon the frame piece in any suitable manner. In the form 80 shown, I have mounted upon the diaphragm an anvil 25, which consists of a rivet-shaped member having a head 26 and a conical point 27. Shock absorbing members 29 are placed between the head and point of the 85 members 25 and the diaphragm. These members are adapted to yield slightly under the shock of the wheel. The force which operates the diaphragm is transmitted 90 through the conical point 27.

An electric motor is illustrated at 30. In the form shown, the frame of this motor consists of an arc-shaped member 31 consisting of a portion of the magnetic circuit of the motor. The poles of the core pieces are 95 preferably cast integral with the member 31, as shown at 32. The field coils 33 are mounted upon the poles. Each of the poles is provided with a lip 34 extending toward the diaphragm. Feet 35 are formed upon the ends of the arc-shaped piece through which the motor is mounted upon the frame piece through any suitable means, such as screws 36.

Upon the left-hand side of the motor, as 105 shown in Figs. 1 and 2, a web 37 is formed over the end of the arc formed by the member 31, which is dropped down into a hanger 38 provided with a bearing for the armature shaft 40. The opening at the other end of 110

the arc is closed by a member 41 connected to the member 31 in any suitable manner, such as by screws 42. The member 41 carries a bracket 45 provided with a bearing 46 for the other end of the armature shaft. The armature 48 is made in any suitable manner and mounted upon the armature shaft which is supported in the bearings previously described. The armature consists 10 of armature laminations 50 and the armature winding 51 mounted thereon. A roughened wheel 60 is provided for operating the diaphragm, in the form illustrated, operating through the member 25. The wheel 60 is mounted upon a hollow member 61 which 15 is fastened to the armature shaft and rotates therewith. The member 61 also carries the commutator 62, so that the wheel 60, the commutator and the member 61 constitute 20 a unitary structure removable from the armature shaft independently of the armature. The wheel 60 is provided with a plurality of openings 70, through which the conductors from the armature to the commutator 25 pass. The wheel 60 is roughened, as shown at 70 by a plurality of serrations, which in running over the point 27 cause the diaphragm to vibrate. The wheel 60 is formed by punching out a cup and indenting the 30 sides thereof to produce the desired serrations. The apparatus is compactly mounted. A portion of the armature coil may extend within the shallow cup formed of the member 60, as illustrated in Fig. 2. The 35 electrical terminals 80 are mounted removably from the frame piece 10, as illustrated in Figs. 1 and 2. When the member 60 is rotated, the roughened surface passing over the member 27 will cause the center of the 40 diaphragm to be displaced, flexing the diaphragm. I believe these vibrations take place in nodes and in other irregular manner, producing a loud signal. The vibrations are forced, regardless of the natural 45 free rate of vibration of the diaphragm.

It will be seen that the apparatus constituting my invention is very compactly mounted, so compactly, in fact, that it forms a flat horn which can be mounted upon the 50 handle bars of a motorcycle, or under the hood of an automobile without occupying space enough to interfere with the operation of the one or the inspection of the apparatus under the hood of the other. It will 55 also be seen that the roughened wheel 60 is mounted to one side of the armature and is removable with the commutator, so that these parts can be removed without taking the armature to pieces.

60 The brushes are shown at 90 carried by the member 41 and spring pressed toward the commutator in a well known manner. When the motor is energized, the roughened wheel 60 is rotated causing the diaphragm 65 to vibrate back and forth in the old and well

known manner, such as is effected in the devices of the Pierman Patent No. 620,958.

The sides 100 of the member 60 are more or less springy, and will yield somewhat in passing over the anvil 27, thereby producing a more mellow tone than if the surfaces were hard and unyielding. The edges of the diaphragm being clamped, the displacement thereof will take place at the center, so that the diaphragm will not be bodily moved 75 when the roughened wheel is rotated. It will be seen that the member 27 is pointed, so that the contact will not be a straight line, but at a point.

I have shown specific details in the specific 80 embodiments illustrated, for the purpose of describing my invention, and not that I wish to be limited either to the form illustrated or the details shown therein, as it will be apparent that many departures may be 85 made from both the form and the details, without departing from the spirit of the invention.

I claim:

1. In an automobile horn, the combination 90 of a flat frame piece having an opening therein, a casing front, a diaphragm mounted between the casing front and the frame piece, an electric motor on the back of the frame piece having an armature shaft substantially parallel to the diaphragm, an armature on said shaft, a commutator on said shaft and a roughened wheel on said shaft between the armature and the commutator adapted to be rotated when the armature 95 shaft is rotated, and means through which said roughened wheel vibrates said diaphragm when the motor is operated.

2. In an automobile horn, the combination 105 of a vibratile diaphragm, supporting means therefor, an electric motor, an armature shaft for said motor mounted substantially parallel to the diaphragm, an armature and a commutator on said shaft, and a roughened wheel between the armature and commutator 110 adapted to be rotated when the armature is rotated and to cause the actuation of the diaphragm.

3. In an automobile horn, the combination 115 of a flat frame piece having an opening therein, a casing front, a vibratile diaphragm clamped between said front and frame piece, said diaphragm being exposed at the rear through the opening, an electric motor mounted on the back side of the frame piece, 120 a rotary armature for said motor mounted on one side of the center of the diaphragm, a commutator for said motor on the other side of the center of the diaphragm, an armature shaft carrying said armature and commutator, and a roughened wheel mounted upon said shaft between the armature and commutator and adapted to be rotated when the armature is rotated to cause the actuation 125 of the diaphragm.

4. In an automobile horn, the combination of a diaphragm, supporting means therefor, a rotary electric motor having an armature and armature shaft, a roughened wheel for operating the diaphragm, a commutator and a supporting member for said commutator and roughened wheel, said roughened wheel, commutator and supporting member being mounted upon the armature shaft and removable therefrom as a unitary structure.
5. In an automobile horn, the combination of a vibratile diaphragm, supporting means therefor, an electric motor including an armature shaft normally mounted substantially parallel to the diaphragm, an armature and a commutator on said shaft, a roughened wheel on said shaft between the commutator and armature adapted to cause the actuation of the diaphragm when the armature is operated, said wheel being provided with openings and conductors connecting the commutator and armature passing through said openings.
6. In an automobile horn, the combination of a vibratile diaphragm, supporting means therefor, an electric motor including an armature shaft, an armature and a commutator on the shaft and a roughened wheel on the shaft between the armature and the commutator and means to transfer motion from the wheel to the diaphragm.
7. In an automobile horn, the combination of a vibratile diaphragm, supporting means therefor, an anvil on the diaphragm, an electric motor, a roughened wheel on the motor between the armature and the commutator adapted to engage said anvil when the motor is operated to cause the diaphragm to vibrate to sound a signal.
8. In an automobile horn, the combination of a flat frame piece having a large opening in the central portion thereof, a vibratile diaphragm extending over said opening and exposed at the rear through said opening, a casing front, means to connect the front, the diaphragm and the frame piece together, an anvil on the diaphragm, an electric motor mounted on the back side of the frame piece and a roughened wheel on the armature shaft of the motor between the commutator and the armature adapted to engage said anvil when the armature is rotated to cause the diaphragm to actuate.
9. In an automobile horn, the combination of a vibratile diaphragm, supporting means therefor, an electric motor mounted on one side of the center of the diaphragm, a commutator for said motor and a roughened wheel on the motor between the armature and commutator for causing the actuation of the diaphragm.
10. In an automobile horn, the combination of a flat frame piece having a large opening in the central portion thereof, a diaphragm extending across said opening and exposed at the rear through said opening, a casing front mounted in front of the diaphragm, means to connect the front, the diaphragm and the frame piece together, an electric motor mounted on the back side of the frame piece with its armature upon one side of the center of the diaphragm, a portion of the armature extending into the opening in the frame piece, the commutator of the motor being to the other side of the center of the diaphragm, an anvil on the diaphragm in the central portion thereof, and a roughened wheel carried by said motor between the armature and the commutator adapted to engage the anvil when the motor is rotated to cause the actuation of the diaphragm.

In witness whereof, I have signed my name in the presence of two witnesses this 24th day of July, 1914.

RAY H. MANSON.
